UNITED STATES PATENT OFFICE.

WILLIAM D. ISAACS, OF NEWARK, NEW JERSEY.

UMBRELLA OR PARASOL.

SPECIFICATION forming part of Letters Patent No. 269,861, dated January 2, 1883.

Application filed July 13, 1882. (No model.)

To all whom it may concern:

Be it known that I, WILLIAM D. ISAACS, of Newark, in the county of Essex and State of New Jersey, have invented a new and useful 5 Improvement in Umbrellas and Parasols, of which the following is a specification.

My invention relates to the caps used to cover the tips of umbrella and parasol ribs, wherein I provide a spring to press up the said caps and 10 prevent their working down, so as to cease to hold the tips; and it consists in the devices substantially as hereinafter set forth.

Figure 1 is a sectional elevation. Fig. 2 is an outside elevation showing a modification.

15 In my construction I connect directly with the cap A a spiral spring, B, having one end resting against a shoulder, C, of said cap, and the other against the end of the handle S. The cap moves freely on the sleeve D on the stick 20 E, and has a flange end, F, made to enter the spring, the coil having an end wound up over this flange end. On the sleeve is a circular rib or bead, G, to prevent the cap from being pressed up to far. When the cap has been 25 pressed down off from the tips L the spring will react it; and when once the tips are inserted in the cap the spring will hold the cap in position, so that they will not be disengaged.

In the form I have described, and shown in Fig. 2, the spring lies out in sight; but it may be desirable to have the spring concealed, and to provide for that I put over the spring a case, H, having one end flanged and resting against a bead, O, on the sleeve, with the spring inside of the flange, and having the other end made to cover the flange K on the cap, as seen in Fig. 1. In this form, when the cap is pressed down to release the tips the flange K moves inside of the case, this flange supporting the end of the case; but this flange is not required when the spring is uncovered.

I claim—

1. The combination of the sleeve D, having the rib or bead G, the cap A, provided with the flange end, F, entering the spring, and the spring B and handle S, substantially as and for the purpose specified.

2. The combination of the sleeve D, having the beads G and O, the cap provided with the flanges F and K, the spring B, and case H, substantially as and for the purpose set forth.

WILLIAM D. ISAACS.
